COMBINATION CRANE AND BULLDOZER

Ervin A. Brugger, Newton, Iowa, assignor to
Koehring Company, Milwaukee, Wis., a corpora-
tion

Application August 19, 1946, Serial No. 691,445

5 Claims. (Cl. 37—116)

1

The object of my present invention has been to produce a combination machine, including power crane and bulldozer features, utilizing the common type of dragline or clamshell crane construction, in conjunction with mounting means on the crane for supporting a bulldozing blade or attachment.

A main advantage achieved by the invention lies in the fact that according to my construction I obtain a combined machine useful for operation for ordinary crane purposes, and one in which the traveling crane body is equipped with a bulldozing blade, so that the crane may be used for operation of the latter, thus doing away with the necessity, when bulldozing operations are desired, of employing a separable bulldozing machine as known in the art.

In the carrying out of my invention I utilize the regular traveling crane body unit with its bucket supporting boom and the other customary instrumentalities involving primarily the cable operating means for a drag bucket or a clam shell bucket, the body unit having attached thereto as an attachment, which may be displaced or retained permanently on the body unit, the bulldozing blade feature. I further utilize the cable operating means for the crane for supporting and adjusting the bulldozing blade when the crane is being used for bulldozing operations, thus eliminating the necessity, in this connection, of using separate and independent adjusting instrumentalities. I furthermore make provision for the supporting of the bulldozing blade independently of the cable operating means of the crane, something which is desirable under certain conditions of use of the combined machine, especially when the crane, for instance, is being used for dragline bucket operation, and the bulldozing blade is desired to be employed, while the dragline bucket is in place, to run up to the bank and push the surplus dirt or material back into the pit for enabling the bucket to take the next bite, including such pushed back material.

According to my invention the bulldozing blade is mounted so that it may be adjusted to different positions, including a position parallel with the transverse axis of the crane for straight dirt-pushing work, and also adjusted to positions at either of opposite angles to such transverse axis to operate as an angledozer for grading roads or the like.

It will be apparent that many owners that use cranes around their yards to unload cars have occasion quite frequently to use a regular bulldozer machine for other purposes, such as to

2

grade the roads around the yard, so that by the employment of my invention the combination machine may be employed for the usual purposes of the crane, as well as the usual purposes of a bulldozer, thus saving the owner the necessity of purchasing a separate bulldozing machine, a unit which is relatively costly, because in addition to the bulldozing blade feature, it comprises a regular traction machine usually of the crawler type with included power plant.

A preferred employment of my invention is illustrated in the accompanying drawings, in which

15 Figure 1 is a perspective view of a common conventional type of dragline crane, showing my bulldozing attachment applied thereto with the operating cables of the crane connected to the bulldozer attachment for supporting and adjusting the blade of the latter.

20 Figure 2 is an enlarged view bringing out more clearly the mounting means for the bulldozing blade upon the side frames of the crawlers of the crane.

25 Figure 3 is a vertical section taken about on the line 3—3 of Figure 2.

Figure 4 is a vertical section taken about on the line 4—4 of Figure 2 more fully showing the universal joint feature, connecting the blade and one of the supporting arms.

30 Figure 5 is a sectional view taken about on the line 5—5 of Figure 2.

Figure 6 is a largely diagrammatic view, showing the bulldozer attachment in full lines and its general arrangement or mounting in relation to the traveling base of the crane, the latter shown in dotted lines.

35 Figure 7 is a perspective view somewhat diagrammatic in illustrating the body of the crane, which is shown in dotted lines and disclosing primarily the operating drums of the crane and their connections through the crane cables, to the bulldozer blade supporting arms.

40 Describing my combination machine invention in detail and referring to Figures 1 and 7, the crane illustrated is a known form of dragline crane such as manufactured today and includes as the main features thereof the swing or rotating body 1 supported upon a crawler base which includes the crawler frames 2, the endless crawler belts 3 usually made up of sectionally connected shoes not shown, and the boom 23. This crane as seen in Figure 7 has operating mechanism on the crane body 1 including the hoist drum 4 for operating the hoist cable 5 of a dragline bucket and

the drag cable drum 6 for operating the drag cable 7 of such a bucket.

The said cables 5 and 7 may be disconnected from the bucket when desired to use the crane for bulldozing purposes, and attached to my bulldozing attachment, which includes a construction comprising the usual bulldozing blade 8. The blade 8 is connected at its opposite ends by spaced side arms 9 with the front end portions of the crawler frames 2. The connection of the arms 9 with the frames 2 as seen in Figure 2 may be detachable and includes trunnions 10 projecting outwardly from the frames 2 and passing through bearing members 11 at the rear ends of the arms 9, the arms 9 being prevented from displacement normally by any suitable means, such as large cotter pins 12.

The arms 9 include further adjustable or extensible sections 13 adapted to be held in position by cross bolts 14 to maintain the members 9 and 13 at fixed adjustments.

Near their front ends the arms 9 are equipped with loops 15, the loop of one arm being connectable with the cable 5 and the loop of the other arm connectable with the cable 7 as seen in Figure 7.

At its front end the arm section 13 is equipped with a universal joint unit 16 interconnecting each member 13 with a bolt member 17 that passes through the blade 8.

For the purpose of using my bulldozer attachment as seen in Figure 1 to create my combination bulldozer and crane machine, it is only necessary to modify the construction of the crane by adding thereto, two sheave blocks 18 and 19, the sheave of the block 18 having the cable 7 trained thereover and the sheave of the block 19 having the cable 5 trained thereover.

By the use of the cable drums 4 and 6 and their customary operating mechanism, the cables 5 and 7 may be simultaneously actuated to raise and lower the blade 8 to proper working or non-working elevations. Actuation of one of the drums 4 or 6 to cause a winding of one of the cables 5 or 7 thereon, may be effected to cause transverse tilting of the bulldozer 8 on the pivots 17, to permit use of the machine for sloping bulldozing operation.

If desired the blade 8 may be equipped with a central loop 21, see Figure 1, and Figure 7 and thus supported by a single cable or part suspended from the boom 23.

The longitudinal relative adjustment of each arm 9 and its section 13 will be availed on, of course, when one arm is desired to be lengthened for angular adjustment of the blade 8 for angle-dozing purposes involving pushing of the dirt toward one side of the crane when the latter is operated for forward movement. The universal joint unit 16 provides for the necessary movement of the blade 8 relatively to the arms 9-13 to obtain all of the various adjustments required for operating purposes of the blade. By operating the drums 4 and 6 independently after removal of the bolts 14, a selected end of the bulldozer 8 may be moved forward relatively to the other end to change the angle of disposition of the blade 8; so that it is disposed at an angle with an end advanced in either direction relative to the transverse axis of the crane, for angle-dozing purposes.

It will be apparent from the foregoing that my invention enables the use of an ordinary crane as a bulldozer by merely mounting the bulldozing blade on the crane, and thus dispensing with the

separate traction unit ordinarily employed to operate bulldozing blades.

The blade 8 is braced in its connections to the arms 9 by means of telescopic adjustable braces 22.

Having thus described my invention, what I claim as new and desire to secure by Letters Patent of the United States is:

1. In combination, an excavating crane including a traveling crane body traction base, a bucket supporting boom, a bulldozing attachment including a pair of relatively movable arms and means for supporting a blade at the outer ends of said arms for pivotal transverse movement relative the traction base, and independent cables carried by the boom adapted for operating an excavating bucket that may be carried by the boom, one of said cables being connected with the attachment near one end of the blade, and another of said cables being connected with the attachment near the other end of the blade, together with means for operating said independent cables.

2. In combination, an excavating crane including a traveling crane body traction base, a bucket supporting boom, a bulldozing attachment including a pair of relatively movable arms and means for supporting a blade at the outer ends of said arms for pivotal transverse movement relative the traction base, and independent cables carried by the boom adapted for operating an excavating bucket that may be carried by the boom, one of said cables being connected with the attachment near one end of the blade, and another of said cables being connected with the attachment near the other end of the blade, together with means for operating said independent cables, said cables being trained from the forward part of the boom rearwardly to points of connection with the attachment, and said cables leading downwardly from the boom to the attachment.

3. In combination, an excavating crane including a traveling crane body traction base, a crane body and a bucket supporting boom on the body, and a bulldozing attachment including a blade mounted at the front end of the crane on and in advance of the traction base, and independent cable means carried by the boom adapted for actuation of an excavating bucket that may be used with the crane, in opposite directions, connected to support the blade at opposite ends, and supporting the attachment, and operating members for the cable means separately operable to raise and lower either end of the blade and supported on the crane body.

4. In combination, an excavating crane including a traveling crane body, a traction base, and a bucket supporting boom, and a bulldozing attachment including a blade mounted at the front end of the crane on and in advance of the traction base and independent cables adapted for operating an excavating bucket that may be carried by the boom, supported on the boom and having separate operating connections with the attachment located adjacent to opposite ends of the blade, and drums on the crane body, one for each of said cables, operable to raise or lower the end of the blade adjacent to which its cable is attached, said cables supporting the attachment at its front portion.

5. The combination claimed in claim 4, in which the cables are trained from a forward portion of the boom rearwardly toward their points of connection with the attachment; combined

with arms comprising sections and connecting the blade at opposite ends to the traction base rearwardly of the cables, and members detachably connecting the sections of the arms.

ERVIN A. BRUGGER.
